UNITED STATES PATENT OFFICE

THEOLA T. ELLIS, OF ST. LOUIS, MISSOURI.

COMBINATION SCOOP AND SCALE.

No. 873,850.

Specification of Letters Patent.

Patented Dec. 17, 1907.

Application filed March 4, 1907. Serial No. 360,402.

To all whom it may concern:

Be it known that I, THEOLA T. ELLIS, a citizen of the United States, residing at St. Louis, State of Missouri, have invented certain new and useful Improvements in a Combination Scoop and Scale, of which the following is a specification, reference being had therein to the accompanying drawing.

My invention relates to improvements in scoops used by grocers and others, and more particularly such devices containing scales whereby their contents may be weighed.

The object of the invention is to provide a combination scoop and scale of this character which will be of simple and comparatively inexpensive construction, and strong and durable in use.

With the above and other objects in view, the invention consists in the novel construction, combination and arrangement of parts hereinafter fully described and claimed, and illustrated in the accompanying drawings, in which

Figure 1 is a front elevation of my improved combination scoop and scale; Fig. 2 is a longitudinal section taken on the plane indicated by the line 2—2 in Fig. 1; Figs. 3 and 4 are transverse sections, on an enlarged scale, taken respectively on the planes indicated by the lines 3—3 and 4—4 in Fig. 1; Fig. 5 is an enlarged detail section taken on the plane indicated by the line 5—5 in Fig. 1; and Fig. 6 is a detail transverse section through the handle showing one of the guide rollers which may be used therein.

The body or bowl 1 of the scoop may be of any desired form and construction and depending from the center of its bottom are inner and outer concentric cylindrical sleeves or stems 2, 3. The inner one 2 is of greater length than the outer one 3 and they are spaced apart to receive between them a third cylinder or sleeve 4 which forms a handle.

The cylinders 2, 3 are adapted to slide freely upon the upper end of the cylinder 4 when the latter is held in an upright position in the hand and they are prevented from turning or rotating by forming at diametrically opposite points upon the cylinder 4 longitudinally extending guide ribs 5 which enter and slide in similarly arranged guide grooves 6 in the outer cylinder 3. The ribs 5 and grooves 6

are preferably but not necessarily formed by crimping the sheet metal of which said cylinders are formed, as clearly shown in Fig. 3 and 4 of the drawings. In the outer cylinder 3 is formed a longitudinally extending opening 7 at one or both edges of which is a scale 8 with which co-acts an indicator 9 carried by the handle cylinder 4. As illustrated in the drawings, the opening 7 is so located that the guide rib 5 at the front of the device is adapted to move centrally through it and the pointer or indicator 9 is secured by a screw or other fastening upon said rib so that it lies within the slot or opening 7, as more clearly shown in Fig. 3. The indicator may however, be mounted in any other suitable manner upon the handle. The body of the scoop is held elevated so that the cylinders 2, 3 engage the upper end of the handle cylinder 4 and the indicator 9 alines with the zero mark of the scale 8, by a coil spring 10 arranged within the cylinders 2, 4 with its upper end bearing against the bottom of the bowl 1. The lower end of the spring is suitably secured to a screw cap or other removable closure 11 in the bottom of the handle cylinder 4. Upon the lower end of the inner guide cylinder 2 is provided a flange or projection 12 which is held by the spring 10 normally in engagement with a similar flange or projection 13 upon the handle cylinder 4. These flanges or projections are so disposed that they limit the sliding movement of the two sections of the scale and cause the indicator 9 to normally register with the zero mark of the scale.

In order to lock the two sections of the scale together, that is, lock the handle cylinder 4 rigidly to the cylinders 2, 3 and hence the scoop bowl so that the device may be used as an ordinary scoop, I form upon the outer face of the cylinder 2 a longitudinally extending row of serrations or teeth 14 which are adapted to be engaged by similar serrations or teeth upon a head 15 carried by the inner end of a radially projecting stem 16 which projects through and slides in an enlargement 17 formed in the handle cylinder 4, as clearly shown in Figs. 1 and 5. The stem 16 has a head or push button 18 upon its outer end and upon its inner portion is an annular flange 19 which is engaged by a spring 20 secured in the enlargement 17.

The spring 20 serves to force the stem 16 outwardly and to hold the jaw or head 15 of the push button away from the serrations 14. When the button 18 is pressed inwardly the 5 jaw 15 will engage the serrations 14 and thus clamp the handle section to the inner sleeve 2. It will be observed that the push button 18 is so located that it will be pressed inwardly when the handle cylinder 4 is 10 grasped as the scoop handle is usually grasped by a person desiring to use it, and at the same time said handle cylinder may be held in a vertical position in the hand with the push button released. While the scale 8 15 is graduated so as to represent five pounds, it will be understood that scale graduations of any description may be employed.

In Fig. 6 of the drawings I have illustrated a roller 26 journaled in a slotted portion 25 of 20 the handle 4 and adapted to project into and run in the groove 6 in the cylinder 3. Any desired number of the rollers 26 may be provided for preventing the parts from turning upon each other and for guiding them in 25 their sliding movement.

Having thus described my invention what I claim and desire to secure by Letters Patent is:

1. A combination scoop and scale comprising a scoop bowl, concentric cylinders depending from said bowl, the outer one having a guide groove, a vertical opening and scale graduations adjacent to the latter, a cylindrical handle to enter between said cylinders, a guide rib upon the handle cylinder to slide in the guide groove in the outer cylinder, an indicator arranged in the opening in the outer cylinder and secured upon the handle cylinder to co-act with said scale 30 graduations, a sliding dog carried by the handle cylinder to engage said inner cylinder and lock said parts together and a coil spring arranged within the inner cylinder and the handle cylinder, for the purpose specified.
- 40 2. A combination scoop and scale comprising a scoop bowl, depending concentric cylindrical sleeves upon the bottom of said bowl, the inner sleeve being of greater length and having serrations upon its outer face and 45 the outer cylinder being spaced from the inner one and having longitudinal guide grooves arranged at opposite points, a vertical opening intersecting one of said grooves and scale graduations adjacent to said opening, a handle cylinder arranged to slide between the inner and outer cylinders and having at opposite points outwardly projecting longitudinally extending guide ribs to enter the grooves in the outer cylinder, an indicator arranged in the opening in the outer cylinder and secured upon the upper end of one of the ribs of the handle cylinder for co-action 50 with said scale graduations, a removable closure at the bottom of said handle cylinder.

55 6. A combination scoop and scale comprising within the handle cylinder and the inner cylinder, a spring retracted push button stem mounted for radial sliding movement in the handle cylinder and a serrated head upon the inner end of said stem to engage the serrations upon the inner 70 cylinder, substantially as shown and described.

75 3. A combination scoop and scale comprising a scoop bowl, inner and outer tubular stems depending from said bowl, the outer one having a longitudinally extending guide groove, said outer stem also having a vertical opening, scale graduations adjacent to said opening, a tubular handle to enter between said tubular stems, a longitudinally 80 extending guide rib upon said handle to slide in said guide groove in the outer stem, an indicator carried by the handle and arranged in the vertical opening in the outer stem to co-act with said scale graduations and a coil 85 spring arranged within the inner stem and said handle, substantially as described.

90 4. A combination scoop and scale comprising a scoop bowl, inner and outer tubular stems depending from said bowl, the outer one having longitudinal grooves, said outer stem also having a vertical opening intersecting one of said grooves, scale graduations adjacent to said opening, a tubular handle to enter and slide between said stems, 95 longitudinal guide ribs upon said handle to enter said guide grooves in the outer stem, an indicator arranged in the vertical opening in the outer stem and secured to one of the guide ribs of the handle for co-action 100 with said scale graduations and a coil spring arranged in the inner stem and handle, substantially as described.

105 5. A combination scoop and scale comprising a scoop bowl, inner and outer tubular stems depending from said bowl, the outer stem having longitudinal guide grooves, said outer stem also having a vertical opening intersecting one of said grooves, scale graduations adjacent to said opening, a tubular 110 handle to slide between said stems, guide ribs upon said handle to enter and slide in the grooves in the outer stem, an indicator arranged in the vertical opening in the outer stem and secured upon one of said ribs of the 115 handle for co-operation with said scale graduations, a coil spring arranged within the handle and the inner stem and means for locking the handle against sliding movement between said stems, substantially as 120 described.

125 6. A combination scoop and scale comprising a scoop bowl, inner and outer tubular stems depending from said bowl, the inner stem being of greater length than the outer one and having a roughened surface, said outer stem having a vertical opening and scale graduations adjacent thereto, a tubular

handle to slide between said stems and carrying an indicator arranged in the opening in the outer stem for co-action with said scale graduations, a coil spring arranged within the inner stem and handle, a spring retracted push button stem mounted for radial sliding movement in the handle and a roughened or serrated head upon the inner

end of said push button stem to engage the roughened surface of the inner stem. 10

In testimony whereof I hereunto affix my signature in presence of two witnesses.
